DESIGN FOR BREAD TOAST

Stanley S. Langendorf, San Francisco, Calif., assignor to Langendorf United Bakeries, Inc., San Francisco, Calif., a corporation of Delaware

Application February 28, 1936, Serial No. 61,412

Term of patent 14 years

To all whom it may concern:

Be it known that I, Stanley S. Langendorf, a citizen of the United States, and residing at the city and county of San Francisco, and State of California, have invented a new, original, and ornamental Design for Bread Toast, of which the following is a specification, reference being had to the accompanying drawing, forming a part hereof.

Fig. 1 is a perspective view of a piece of bread toast showing my new design; and

Fig. 2 is a sectional view taken on line 2—2 of Fig. 1. Both sides of the slice are alike.

I claim:

The ornamental design for bread toast, substantially as shown and described.

STANLEY S. LANGENDORF.
